LOUDSPEAKER

Harry F. Olson, Haddon Heights, N. J., assignor
to Radio Corporation of America, a corpora-
tion of Delaware

Application January 31, 1940, Serial No. 316,614

15 Claims. (Cl. 179—115.5)

This invention relates to loudspeakers, and more particularly to mechanical networks therefor for controlling the high frequency response thereof.

It is quite well known that, in general, in radio and other forms of sound reproducing apparatus, it is often desirable to attenuate the response above a certain high frequency limit. In some cases, it may be desirable to attenuate a certain band, as, for example, 10,000 cycles and over in radio reproduction, to eliminate the adjacent channel beat note. To accomplish this, there have been provided electrical networks and filters in the radio frequency, intermediate frequency, and audio frequency stages, but such networks and filters are usually quite costly as compared to mechanical filters for certain applications in sound reproduction.

Now, I am aware that attempts have been made heretofore to provide mechanical filters for attenuating the high frequency response of loudspeakers, as shown, for example, in the patent to Carlisle 2,007,750. However, the filters of the prior art of which I am aware do not provide sufficiently high attenuation for all practical purposes, nor do they have as sharp a cut-off as is frequently desired.

The primary object of my present invention is to provide improved mechanical networks for loudspeakers of the dynamic type by means of which the high frequency response may be controlled satisfactorily over a wide range.

More particularly, it is an object of my present invention to provide an improved band elimination mechanical network for loudspeakers by means of which it is possible to suppress certain frequency bands in the high frequency region, or to attenuate the high frequency response.

Another object of my present invention is to provide an improved vibratile system for acoustic apparatus of the dynamic or moving coil type.

Still another object of my present invention is to provide improved mechanical networks as aforesaid which may be readily applied to existing loudspeakers with great facility.

It is also an object of my present invention to provide improved acoustic apparatus as aforesaid which is extremely simple in construction, which readily lends itself to rapid quantity production, which is very inexpensive in cost, and which is highly efficient in use.

In accordance with my present invention, I provide the loudspeaker with a voice coil form which extends through the cone or diaphragm,

the form carrying the usual voice coil on that portion thereof which extends to one side of the diaphragm and having a compliance therein in that portion which extends to the other side of the diaphragm. Preferably, also, a small mass is attached to the end of the voice coil form in which the aforementioned compliance is formed. If desired, the coil form may also be provided with one or more compliances in that portion thereof on which the voice coil is mounted. In any case, a dust cap may be secured to the diaphragm over the end of the voice coil form which carries the mass in order to reduce radiation therefrom. The effect of adding networks of this type is the same as introducing into the equivalent electrical circuit of the vibrating system one or more parallel resonant networks which have the effect of providing sharp cut-off and relatively high attenuation at the higher frequencies.

The novel features that I consider characteristic of my invention are set forth with particularity in the appended claims. The invention itself, however, both as to its organization and method of operation, as well as additional objects and advantages thereof, will best be understood from the following description of several embodiments thereof, when read in connection with the accompanying drawings, in which:

Figure 1 is a view of a loudspeaker with one form of my invention applied thereto.

Figure 2 is the equivalent electrical circuit of the vibrating system shown in Fig. 1.

Figure 3 is a response curve showing the frequency characteristic of the acoustic system of Fig. 1.

Figure 4 shows a loudspeaker system having another form of my invention embodied therein.

Figure 5 is a wiring diagram of the electrical equivalent of the system of Fig. 4.

Figure 6 is a response curve showing the frequency characteristic of the system of Fig. 4.

Figure 7 shows a loudspeaker system embodying still another form of my present invention.

Figure 8 is a wiring diagram of an electrical circuit corresponding to the vibrating system of Fig. 7.

Figure 9 is a response curve showing the frequency characteristic of the system of Fig. 7.

Figure 10 shows a vibrating system incorporating still another form of my invention.

Figure 11 is a wiring diagram of an electrical circuit equivalent to the vibrating system of Fig. 10.

Figure 12 is a response curve showing the frequency characteristic of the system of Fig. 10.

Figure 13 is a fragmentary view of a loud-speaker system embodying still another form of my present invention.

Figure 14 is a wiring diagram showing the electrical circuit equivalent to the system of Fig. 13, and

Figure 15 is a fragmentary view of a modified arrangement of the system shown in Fig. 1.

Referring more particularly to the drawings, wherein similar reference numerals indicate corresponding parts throughout, there is shown, in Fig. 1, a vibratile member in the form of a cone or diaphragm 1 to which is secured a voice coil form 3 which extends through the diaphragm. The diaphragm 1 may be provided with an annular rim or flange 5 which may be clamped in place between a pair of suitable rings 7 in well-known manner and it preferably also has secured thereto a spider 9 for centering the voice coil form 3 in the air gap of a suitable magnetic system (not shown).

The voice coil form 3 has mounted thereon a suitable voice coil 11 on that portion thereof which extends to one side of the diaphragm 1. One that portion of the voice coil form 3 which extends to the other side of the diaphragm 1 (that is, the portion of the voice coil form 3 which is within the cone), there is formed a compliance 13. This may be a corrugation or the like which is rolled into the form 3 during its production. Preferably, also, a ring 15 is secured to the upper end of the voice coil form 3 beyond the compliance 13 to provide a mass on the form 3.

Fig. 2 shows the electrical analogue of the system shown in Fig. 1. It will be noted that the compliance c_2 and the resistance r_2 of the corrugation 13 and the mass m_2 of the ring 15 form a parallel resonant circuit in series with the mass m_1 of the voice coil 11, the compliance c_3 of the spider 9 and the impedance Z_c of the cone 1. The driving force generated in the voice coil 11 is designated as f in the equivalent electrical circuit of Fig. 2. By employing a mechanical network of this sort, the coupling between the voice coil 11 and the cone or diaphragm 1 will be reduced at the resonant frequency of the parallel circuit provided by the mass m_2 , the compliance c_2 and the resistance r_2 . The frequency response characteristic of this system is shown in Fig. 3 from which it will be seen that the response is attenuated about 20 db. at about 10,000 cycles. The attenuation at resonance of the aforementioned parallel circuit is governed by the resistance in the compliance 13. The system just described can be easily fabricated by simply making the voice coil form 3 longer than is customary in conventional loudspeakers and rolling in an appropriate corrugation or compliance 13. The width of the attenuation band is, of course, governed by the constants of the system.

In Fig. 4 I have shown a system which is quite similar to that shown in Fig. 1 but wherein the voice coil form 3 is made somewhat longer and an additional compliance or corrugation 17 is provided therein adjacent the voice coil 11. This has the effect of shunting the series connected compliance c_1 and the resistance r_1 , which correspond to the compliance and resistance, respectively, of the corrugation 13, across the impedance of the cone 1, as clearly shown in Fig. 5. From an inspection of Fig. 3, it will be noted

that, in the system of Fig. 1, the attenuation decreases above the resonance frequency of the parallel circuit constituted by m_2 , c_2 and r_2 . At about 13,000 cycles and above, there is no attenuation. In most cases, however, it is desirable to attenuate the entire band above 10,000 cycles, and this may be accomplished very readily by the system shown in Fig. 4 wherein the compliance 17 is inserted between the voice coil 11 and the cone 1. The response curve of Fig. 6 shows that there is considerably more attenuation at 10,000 cycles and above 10,000 cycles in the system of Fig. 4 than there is in the system of Fig. 1.

In Fig. 7, I have shown still another modification of my invention which embodies a single section filter connecting the voice coil mass m_1 and the cone impedance Z_c , as clearly shown in Fig. 8. This is accomplished by providing an additional corrugation or compliance 19 on the lower end of the voice coil form 3 to provide the additional parallel resonant circuit corresponding to the mass m_3 , compliance c_3 and resistance r_3 where m_3 is the mass of the added portion, or lower end, of the voice coil form 3 below the compliance 19, and c_3 and r_3 are, respectively, the compliance and resistance of the corrugation 19. Since the impedance of the spider 9 is very small, it may be neglected, and the system is therefore effectively a T type low pass filter connecting the voice coil 11 and the cone 1. Very high attenuation may be obtained at the resonance frequency of the two arms of the filter, as represented by the two parallel resonant circuits. The response frequency characteristic of this modification of my invention is shown in Fig. 9, from which it will be noted that, at 10,000 cycles, the attenuation is about 35 db., being also quite high above 10,000 cycles. As in the systems previously described, the additional corrugation 19 may be formed very easily by simply rolling it into the voice coil form 3 along with the corrugations 13 and 17 to provide a single voice coil form having the plurality of corrugations.

Fig. 10 shows a system similar to that of Fig. 7 but wherein the cone 1 is also provided with a corrugation or other suitable compliance 21 adjacent its connection to the voice coil form 3. If the compliance of the corrugation 21 is c_4 and its resistance r_4 , and the mass of that part of the coil form 3 between the corrugations 13 and 17 plus the mass of the part of the cone 1 between the corrugations 17 and 21 is m_4 , the equivalent electrical circuit of this system will be as shown in Fig. 11 with the capacitance c_4 and resistance r_4 shunted across the impedance Z_c , retaining the T type filter which connects the voice coil mass m_1 and the cone impedance Z_c , as in Fig. 8. The response curve of Fig. 12 shows that, at 10,000 cycles, the attenuation of the system of Fig. 10 is about the same as that of Fig. 7, but above 10,000 cycles about 4 db. more attenuation is obtained with the system of Fig. 10 than with the system of Fig. 7.

In Fig. 13, I have shown still another modification of my invention which is similar to that of Fig. 10 but provide an additional form 23 which is secured to the cone or diaphragm 1 concentrically with the voice coil form 3 and on the other side of the corrugation or compliance 21. This provides a two-section filter, as clearly shown in Fig. 14, wherein the mass m_5 corresponds to the mass of the form 23, the com-

pliance c_5 and the resistance r_5 correspond, respectively, to the compliance and resistance of the corrugation 25, and m_6 corresponds to the mass of those portions of the form 23 and the cone 1 which are between the corrugations 21 and 25.

With suitably chosen constants for the system of Fig. 13, it is possible to obtain an attenuation of from 40 to 50 db. at 10,000 cycles. Clearly, a system of this sort can be built at a very low cost compared to an electrical filter having these characteristics. The form 23 can obviously be made in one piece similarly to the voice coil form 3 and its corrugation 25 rolled into it during manufacture, and it may be attached to the cone by a suitable adhesive or in any other desired manner.

In the systems thus far described, there may be considerable radiation from the vibration of the various masses under certain conditions of operation and design. In order to reduce this vibration to a minimum value, a dust cap 27 may be added to the system by securing it to the cone 1 over the upper end of the voice coil form 3, as clearly shown in Fig. 15.

From the foregoing description, it will be apparent to those skilled in the art that I have provided several novel band elimination mechanical networks for loudspeakers for suppressing the response thereof at 10,000 cycles as well as the adjacent channel beat notes. All of the networks described can be built at an extremely low cost and may be easily incorporated in dynamic loudspeakers of otherwise conventional design. Although I have shown and described a number of embodiments of my invention, it will be apparent to those skilled in the art that many changes in the modifications described, as well as many additional embodiments thereof, are possible. For example, instead of using a voice coil as the driving element for the cone 1, any other suitable driver may be used, such as a crystal unit, a magnetic motor, a condenser unit, or any other similar driver, in which case the coupling member between the driver and the cone 1 could be made to extend through the cone and be provided with one or more corrugations similarly to the voice coil form herein described. In fact, wherever I have used the term "voice coil form" throughout the preceding description and in the appended claims, I intend this to include also any form of coupling means between the diaphragm or vibratile member and the driving unit therefor of whatever nature. Accordingly, I desire it to be understood that I do not wish to be limited except insofar as is made necessary by the prior art and the spirit of the appended claims.

I claim as my invention:

1. Acoustic apparatus comprising, in combination, a vibratile member, a voice coil form secured thereto, said form extending through said member with at least one of its ends freely suspended for vibration with said member, a voice coil carried by said form on one side of said member, and a compliance in said form on the other side of said member.

2. Acoustic apparatus comprising, in combination, a vibratile member, a voice coil form secured thereto, said form extending through said member with its ends freely suspended for vibration with said member, a voice coil carried by said form on one side of said member, a compliance in said form on the other side of said member, and means carried by said form

at the end thereof beyond said compliance providing a mass therefor.

3. Acoustic apparatus comprising, in combination, a vibratile member, a voice coil form secured thereto and extending through said member with its ends freely suspended for vibration with said member, and a voice coil carried by said form, said form having a plurality of compliances therein, at least one of said compliances being on that portion of said form which extends to one side of said member and at least one other of said compliances being on that portion of said form which extends to the other side of said member.

15. The invention set forth in claim 3 characterized by the addition of a mass at one end of said form beyond the compliance on that portion of said form terminating in said one end.

5. Acoustic apparatus comprising, in combination, a vibratile member, a voice coil form secured thereto and extending through said member with its ends freely suspended for vibration with said member, a voice coil carried by said form on the portion thereof extending to one side of said member, said portion having at least one compliance therein, and a compliance in the portion of said form extending to the other side of said member.

20. Acoustic apparatus comprising, in combination, a vibratile member, a voice coil form secured thereto and extending through said member with its ends freely suspended for vibration with said member, a voice coil carried by said form on the portion thereof extending to one side of said member, said portion having a plurality of compliances therein in spaced relation along its length and said voice coil lying between an adjacent pair of said compliances, the mass of that part of said voice coil form which lies beyond that one of said pair of compliances which is most remote from said vibratile member cooperating with said last named compliance to form therewith a resonant network, and a compliance in the portion of said form extending to the other side of said member.

25. Acoustic apparatus comprising, in combination, a vibratile member, a voice coil form secured thereto and extending through said member with its ends freely suspended for vibration with said member, a voice coil carried by said form on the portion thereof extending to one side of said member, said portion having a plurality of compliances therein in spaced relation along its length and said voice coil lying between an adjacent pair of said compliances, the mass of that part of said voice coil form which lies beyond that one of said pair of compliances which is most remote from said vibratile member cooperating with said last named compliance to form therewith a resonant network, a compliance in the portion of said form extending to the other side of said diaphragm, and a mass secured to the last named portion of said form at the end thereof beyond said last named compliance.

30. Acoustic apparatus comprising, in combination, a vibratile member, a voice coil form secured to said member and extending through said member with its ends freely suspended for vibration with said member, and a voice coil carried by said form on the portion thereof extending to one side of said member, said form having a compliance in the portion thereof extending to the other side of said member, and

said diaphragm also having a compliance there-in adjacent its connection to said form.

9. The invention set forth in claim 8 characterized in that said first named portion of said form is provided with a pair of longitudinally spaced compliances, and characterized further in that said voice coil is carried on said form between said last named pair of compliances, the mass of that part of said voice coil form which lies beyond that one of said pair of compliances which is most remote from said vibratile member cooperating with said last named compliance to form therewith a resonant network.

10. The invention set forth in claim 8 characterized in that said first named portion of said form is provided with a pair of longitudinally spaced compliances, characterized further in that said voice coil is carried on said form between said last named pair of compliances, the mass of that part of said voice coil form which lies beyond that one of said pair of compliances which is most remote from said vibratile member cooperating with said last named compliance to form therewith a resonant network, and characterized still further by the addition of a mass on the end of the second named portion of said form.

11. Acoustic apparatus comprising, in combination, a vibratile member, a voice coil form secured thereto and extending through said member, a voice coil carried by said form, said form having at least one compliance therein on that portion thereof which extends to one side of said member and at least one other compliance therein on that portion thereof which extends to the other side of said member, and a second form secured to said member in concentric relation to said voice coil form and on that side of said member which is remote from said voice coil, said second form also having a compliance formed therein.

12. Acoustic apparatus comprising, in combination, a vibratile member, a voice coil form secured thereto and extending through said member, a voice coil carried by said form on the portion thereof extending to one side of said member, said form having a compliance in the portion thereof extending to the other side of said member, means on the end of said last named portion providing a mass thereon, and a cap secured to said member over said last named portion of said form for reducing radiation from said means.

13. Acoustic apparatus comprising, in combination, a vibratile member, a driving element therefor, and means coupling said element to said member, said coupling means extending through said member and having at least one of its ends freely suspended for vibration with said member, said coupling means also having a plurality of compliances therein, at least one of said compliances being formed in that portion of said coupling means which extends to one side of said member and at least one other of said compliances being formed in that portion of said coupling means which extends to the other side of said member.

14. Acoustic apparatus comprising, in combination, a vibratile member, a driving element therefor located to one side of said member, and means coupling said element to said member and extending through said member beyond the other side thereof, said means having a compliance therein in its extension beyond said other side and the end of said extension being freely supported for vibration with said member.

15. The invention set forth in claim 14 characterized by the addition of a mass on said freely supported end of said extension.

HARRY F. OLSON.
